UNITED STATES PATENT OFFICE.

JAMES O. PARKER AND VIVA M. PARKER, OF LAKIN, KANSAS.

MUSIC-LEAF TURNER.

1,253,092.

Specification of Letters Patent.

Patented Jan. 8, 1918.

Application filed July 24, 1917. Serial No. 182,507.

To all whom it may concern:

Be it known that we, JAMES O. PARKER and VIVA M. PARKER, citizens of the United States, residing at Lakin, in the county of 5 Kearny and State of Kansas, have invented new and useful Improvements in Music-Leaf Turners, of which the following is a specification.

Broadly stated, the invention comprehends 10 the provision of an apparatus by means of which the leaves of musical compositions can be turned at any time, and in either direction by depressing a foot pedal, thus doing away with the custom of turning the leaves 15 by hand, which usually results in interruptions in the playing of the instrument.

Other objects, as well as the nature and advantages of the invention will be better understood when the following detail description is read in connection with the accompanying drawings, the invention residing in the construction, combination and arrangement of parts as claimed.

In the drawings forming part of this 25 specification like numerals of reference indicate similar parts in the several views and wherein:—

Figure 1 shows a front elevation of the apparatus positioned upon a piano, the latter 30 being indicated by dotted lines.

Fig. 2 is a side elevation of the turning mechanism.

Fig. 3 is a horizontal sectional view taken 35 on line 3—3 of Fig. 2.

Fig. 4 is a transverse sectional view taken on line 4—4 of Fig. 2.

Fig. 5 is a sectional view taken on line 5—5 of Fig. 2.

The apparatus forming the subject matter 40 of our invention essentially consists of a substantially U-shaped frame 10 upon which is supported the main part of the mechanism for turning the leaves of the musical composition. One of the parallel limbs 11 of the frame is extended upwardly as at 12 so that the terminal 13 of said limb will be disposed in close relation to the remaining parallel limb 11' of the frame 10. Fixed 45 between the extremities of the parallel limbs 50 of the frame 10, is a vertically disposed shaft 14, while mounted upon said shaft for rotation is a plurality of sleeves 15, the latter being disposed in spaced superimposed relation. For each sleeve is provided a disk-like 55 plate 16 which is keyed upon the shaft 14 immediately beneath its respective sleeve. The

upper surface of the disk-like plate 16, and the confronting face of the sleeve 15 are formed with oppositely disposed annular recesses 17 and 18 respectively, these recesses unitedly defining a raceway for roller bearings 19, whereby the sleeve 15 can be easily rotated in the manner to be hereinafter described. Carried by each sleeve 15 is a horizontally disposed arm 20 from which is suspended a 60 music sheet 21. For this purpose a plurality of spring clips 22 are preferably employed for sliding adjustment on the arm 20, the upper surface of which is provided with teeth 23 with which clips 22 coöperate with 65 a view of holding said clips fixed relatively to the arm in any adjusted position. Depending from one of the clips 22 is a yoke 24 in which is journaled a guide pulley 25, and over which is trained a flexible element such 70 as a chain or the like indicated at 26, one end of the latter being secured to the other clip 22, while the opposite or lower end of the chain has associated therewith a spring 75 clasp 27 which supports the sheet music in 80 the manner illustrated. The clips 22 can be moved toward and away from each other to vary the length of the flexible element as the occasion may require. Inclosing the shaft 14 and its associated parts, is a semicylindrical casing 28 having end walls 29 which are secured in any suitable manner to the parallel limbs of the frame 10. It might here be 85 stated that any number of sleeves 15 and arms 20 may be associated with the shaft 14 90 as desired, while the casing 28 is provided with a transverse slot 30 for each of the arms 20, the latter projecting through the slots 30 of the casing to move therethrough from one side of the casing to the other. The shaft 95 14 is provided at opposite sides with flat portions 31, while carried by any one or more of the sleeves 15 is a pair of leaf springs 32 adapted to extend across the flat portions 31 of the shaft to hold the latter in proper position, subsequent to the rotation thereof for 100 the purpose of turning a sheet of music.

Journalized between the parallel limbs of the frame 10 is a vertically disposed shaft 33 from which projects a plurality of horizontally disposed arms 34. The arms 34 are provided to turn one of the sleeves 15 upon each quarter of a revolution of the shaft 33, and with the turning of said sleeve 15 the arm 20 carried thereby is swung 110 one hundred and eighty degrees from one side of the casing 28 to the other. Conse-

quently the arms 34 project from the shaft 33 at different points and in different directions, or in other words the arms are disposed relatively so that each of the sleeves 15 is 5 rotated in successive order from one end of the shaft 14 to the other. It will be observed that each of the arms 20 is provided with a forked extremity, and the fingers 35 of said extremity are disposed in the 10 path of movement of the arms 34, to be engaged by the latter for the purpose of rotating the sleeves 15 and the arms 20. The actuating extremities of the arms 34 are offset as at 36 and support a roller 37 to 15 prevent binding between the parts when the shaft 33 is rotated. Also supported on each arm 34 is a cross arm 38, the opposite extremities of which are offset as at 39 and support the rollers 40. Manifestly each 20 arm 34 is provided with a plurality of rollers disposed in triangular relation, so that when the arms 34 are rotated with the shaft 33 the rollers 37 and 40 engage the fingers 35 of the forked extremities of the arms 20 in 25 successive order, to insure positive movement of the arms 20 to the limit of their adjustment. When it is stated that the rollers 37 and 40 engage the fingers 35 in successive order, it is to be understood that this 30 fact depends upon the direction of rotation of the shaft 33. By reason of the triangular relation between the rollers 37 and 40, it is clear that the fingers 35 of the forked extremities of the arms 20 will be continuously engaged by the rollers while the particular arm 20 is being swung from one side of the casing to the other. The shaft 33 is formed with a plurality of flat surfaces or portions 41 with which a plurality of 35 leaf springs 42 coöperate to maintain the shaft fixed in its adjusted position subsequent to each rotation thereof. The springs 42 are terminally secured to the frame 10, while the corresponding free extremities of 40 the springs are adapted to engage the flat surfaces or portions 41 of the shaft for the purpose just mentioned.

While any suitable means may be utilized for rotating the shaft 33, we preferably 50 make use of a pair of spaced vertically disposed rods 43, the lower extremity of which being connected with a foot pedal 44. The pedals 44 are conveniently disposed at the opposite sides of the ordinary pedals of the 55 instrument. The upper extremity of each of the rods 43 is secured to the relatively short branch 45 of a bell crank lever which is pivotally mounted at its apex upon a bracket 46, while pivotally associated with 60 the extremity of the longer branch 47 of the bell crank lever is a horizontally disposed reciprocating rod 48. Each rod 48 has pivotally connected with the free extremity thereof a dog 49 which coacts with 65 a sleeve 50 keyed upon the shaft 33 to rotate

the latter. Also keyed upon the shaft 33 for rotation therewith are collars 51, the latter being disposed at opposite sides of the sleeve 50, while projecting from each collar is a substantially L-shaped member 52, the free extremities of said members projecting toward each other and through openings in the dogs 49 of the respective rods 48, by reason of which arrangement the dogs are fulcrumed at a point intermediate their length. 75

It is to be understood that when one of the pedals is depressed the shaft 33 is rotated in one direction to turn the leaves of music to the left; and when the other pedal is depressed the shaft 33 is rotated in a reverse direction to turn the sheet of music to the right. Consequently the reciprocating rods 48 and their associated dogs operate independently of each other. When one of the 80 pedals is depressed the vertically disposed rod 43 connected therewith is depressed, thus imparting a pivotal movement to the bell crank lever and its associated rod 48 in a direction to cause the dog 49 to have its active extremity moved into one of a plurality of grooves 53 provided in the sleeve 50. During a continued depression of the 85 pedal and its associated parts, the sleeve 50 and shaft 33 are rotated in unison a quarter of a revolution, during which time one of the springs 54 is placed under tension. Simultaneously with the rotation of the shaft 33 one of the collars 51 is also rotated, and by reason of this fact the coil spring 55 90 encircling the L-shaped member 52 and connected therewith at one end with the dog 49 at the other end, is placed under tension. Subsequent to the turning of the sheet music, the pedal is released, at which time the coil 95 spring 55 functionates to throw the dog 49 out of engagement with the sleeve 50, and almost simultaneously with this action the spring 54 functionates to return the 100 pedal and its associated parts to normal position. When it is desired to turn the music in an opposite direction, the other 105 pedal is operated and the operation of the mechanism is accordingly reversed. 110

While it is believed that from the foregoing description the nature and advantages of the invention will be readily apparent, we desire to have it understood that what is herein shown and described is merely 115 illustrative of the preferred embodiment of the invention, and is therefore not to be considered restrictive, as such changes in the construction and arrangement of parts 120 may be resorted to when desired as fall within the scope of what is claimed. 125

What is claimed is:—

1. A music leaf turner comprising a support, a shaft mounted thereon and having a flat portion, a plurality of sleeves mounted for independent rotation on said shaft, a 130

leaf turning arm carried by each sleeve, means for rotating said sleeves, and a leaf spring carried by each sleeve and coöperating with said flattened portion of the shaft 5 to hold said sleeve in adjusted position.

2. A music leaf turner comprising a support, a shaft mounted thereon, a plurality of sleeves mounted for independent rotation on said shaft, a leaf turning arm carried by 10 each sleeve, means for rotating said sleeves, a pair of resilient clips mounted for relative sliding adjustment upon said arm and co-operating therewith to maintain their adjusted position, a pulley journaled upon one 15 of said clips, a flexible element secured at one end to the other of said clips and trained over said pulley, and a spring clasp carried by the opposite end of the flexible element.

3. A music leaf turner comprising a support, a shaft fixed thereon, a plurality of leaf turning arms projecting from the shaft and associated therewith for independent swinging movement, a second shaft rotatably mounted on said support, means carried 20 by the said second shaft for individually swinging said arms at each quarter of a revolution of said shaft, means operable to partially rotate said shaft, and a leaf spring engaging said rotatable shaft and coöperating 25 therewith to hold said shaft immovable subsequent to each operation of the means for rotating the shaft.

4. A music leaf turner comprising a support, a shaft fixed thereon, a plurality of 30 leaf turning arms associated with said shaft

for independent swinging movement, a second shaft rotatably mounted on said support, arms projecting radially from said shaft, a plurality of rollers carried by the outer extremity of said arms and disposed in staggered relation to coöperate with the adjacent extremity of each of the leaf turning arms, to swing the latter in either direction depending upon the direction of rotation of said shaft, one of said leaf turning arms being 45 actuated upon every quarter revolution of the second mentioned shaft, and means for rotating the latter in reverse directions.

5. A music leaf turner comprising a support, a shaft fixed thereon, a plurality of leaf turning arms associated with said shaft for independent swinging movement, one extremity of each arm being forked, a second shaft rotatably mounted upon the support, 50 arms radiating from said second mentioned shaft, rollers carried by the outer extremity of each arm, said rollers being disposed in triangular relation and coöperating with the forked extremity of the adjacent leaf turning arm to swing the latter in either direction 55 depending upon the direction of rotation of the second mentioned shaft, said leaf turning arm being actuated in successive order with each quarter revolution of the second mentioned shaft, and means for 60 rotating said shafts in reverse directions.

In testimony whereof we affix our signatures.
